UNITED STATES PATENT OFFICE.

EMMIT G. LATTA, OF FRIENDSHIP, NEW YORK, ASSIGNOR OF ONE-HALF
TO ADRIAN C. LATTA, OF SAME PLACE.

VELOCIPED.

SPECIFICATION forming part of Letters Patent No. 328,693, dated October 20, 1885.

Application filed March 3, 1885. Serial No. 157,658. (No model.)

To all whom it may concern:

Be it known that I, EMMIT G. LATTA, of Friendship, in the county of Allegany and State of New York, have invented new and 5 useful Improvements in Velocipedes, of which the following is a specification.

This invention relates to an improved construction of the steering-head which enables a long spindle to be used and permits the parts 10 to be quickly adjusted and to be rigidly held in place; also to an improved means for securing the dust-guard to the steering-head, and also to an improved construction of the supporting parts of the rear wheel, whereby the 15 rear wheel is made vertically adjustable in the rear fork.

In the accompanying drawings, consisting of two sheets, Figure 1 is a side elevation of a bicycle provided with my improvements. 20 Fig. 2 is a longitudinal sectional elevation of the steering-head on an enlarged scale. Fig. 3 is a horizontal section in line $x-x$, Fig. 2. Fig. 4 is a horizontal section in line $y-y$, Fig. 2. Figs. 5, 6, and 7 are longitudinal sectional 25 elevations of the upper portion of the steering-head, showing modified constructions of the same. Fig. 8 is a side elevation of the central part of the rear wheel and supporting parts. Fig. 9 is a horizontal section in line $x-x$, Fig. 8. Fig. 10 is a vertical section in line $y-y$, Fig. 8. Figs. 11 and 12 are side elevations showing modified constructions of the 30 support of the rear wheel. Fig. 13 is a horizontal section in line $x-x$, Fig. 11.

35 Like letters of reference refer to like parts in the several figures.

A represents the steering-head, a the spindle arranged in the same and provided with conical ends or centers a' a'' in the usual manner.

40 A' is the neck extending rearwardly from the spindle, and A'' is the perch.

b is the handle-bar lug formed at the front side of the steering-head A, and b' the handle-bar secured therein.

45 C represents the adjusting-screw, which bears against the upper center, a' , and whereby the bearings of the centers in the steering-head are adjusted, and D represents a tubular clamp 50 or check-nut, whereby the adjusting-screw C is secured in the steering-head.

As represented in Figs. 1 and 2, the nut D is provided with an internal screw-thread, which receives the external thread of the screw C, the lower end of the latter, which fits in the upper bore of the steering-head, being made cylindrical and without a screw-thread. The outer side of the nut D is provided with a downwardly-tapering screw-thread, which fits in a corresponding internal thread formed in 60 the upper portion of the steering-head, so that by screwing the nut D down into the steering-head the screw C is clamped and held in place. The nut is preferably split or divided vertically, as represented at d in Fig. 4, whereby 65 it is enabled to close tightly around the screw C in screwing it down into the tapering cavity of the steering-head. By the wedging action of the nut D against the steering-head and screw C the adjusting-screw C is not only 70 firmly locked against turning, but the screw C is also provided with a rigid support around the upper end of the spindle, which prevents all forward or backward movement of the adjusting-screw in the steering-head when the 75 machine is in use. This remedies a serious difficulty existing in the constructions now used, in which a check-nut resting on the top of the steering-head is employed, which is soon worked loose by the strain from the spindle, and 80 causes the latter to swing backwardly and forwardly, whereby the top of the spindle is worn round or oval, which renders it impossible to properly adjust it. The upper portions of the screw C and nut D are preferably reduced in 85 size, as represented in Figs. 2 and 5, to improve the appearance of the steering-head, and the latter is preferably extended upwardly beyond the handle-bar lug, as represented in 90 the same figures, to permit the top of the spindle to project above the lug and be rigidly supported around its upper end; but, if desired, the parts may be constructed as represented in Figs. 6 and 7, in which the top of the steering-head is on a level with the top of 95 the handle-bar lug. In Fig. 7 the screw C is not contracted at its upper end. This construction is less expensive and affords a slightly closer build, and permits the spindle to be made considerably higher with safety, because 100 the nut D supports the adjusting-screw C on the extreme upper end of the nut. The latter

is provided at its upper end with suitable means for receiving a wrench.

In the construction represented in Fig. 2 the nut D is made tapering throughout the 5 entire length of its threaded outer surface.

In the construction represented in Fig. 5 the threaded portion of the nut D is made cylindrical, and the lower end of the nut is made tapering and arranged to fit in a tapering seat 10 in the upper end of the steering-head; or, if preferred, these tapering portions may be arranged at the upper end of the threaded part 15 of the nut.

In the construction represented in Fig. 6 15 the opening in the steering-head is made cylindrical, and the outer threaded surface of the nut D is also made cylindrical, and the inner surface of the bore of the nut is provided with a tapering portion, which bears against the 20 tapering neck of the screw C. The screw-thread of the nut is preferably made quicker or of greater pitch than that of the screw C.

In the construction represented in Fig. 7 25 the screw C is threaded throughout its whole length and screwed both into the nut D and the steering-head. This construction is much stronger, but requires greater exactness in fitting, to insure the proper working of the threads of the parts.

30 In all of these constructions the nut D is wedged between the screw C and the steering-head, whereby the screw C is firmly clamped in position after having been adjusted.

It is obvious that the nuts D may be split 35 throughout their whole length or only a part of their length, and that, if only split for a part of their length, several slots may be formed in the nuts, if desired.

E represents the dust-guard applied to the 40 rear side of the steering-head A to cover the opening in the same through which the neck A' passes.

F represents a spring-clamp, which is seated 45 with its back against a shoulder, f, formed in the under side of the neck A', and which bears with its ends against the dust-guard, the said ends being provided with pins or projections f', which enter openings in the dust-guard. The spring-clamp F holds the guard securely 50 against the steering-head and insures a close fit and prevents noise. Upon slightly raising the spindle in the steering-head the lower end of the spindle can be drawn back far enough to permit the spring F to be put in place or to 55 be removed, and the act of securing the spindle compresses the spring and secures the dust-guard.

It is obvious that the projections may be formed on the dust-guard and the openings in 60 the spring.

G represents the rear fork, and H represents the rear wheel arranged between the jaws of the rear fork.

h is the hub of the rear wheel, h' h'' the cones 65 arranged on the inner sides of the fork-arms and projecting into the hub, h''' the balls in-

terposed between the cones and the annular grooves in the hub, and I the supporting-bolt which passes axially through the rear wheel and its supporting parts.

J represents lugs or plates formed at the 70 lower ends of the arms of the fork G and supporting the bolt I.

In the construction represented in Figs. 8 and 10 the lugs J are constructed with vertically-elongated openings j, through which 75 the bolt I passes, and in which the bolt is made vertically adjustable.

i represents the head of the bolt, and i' the screw-nut applied to the opposite end of the 80 bolt.

K is a washer interposed between the screw-nut i' and the adjacent outer side of the lug J. The washer K is provided on its rear side with one or more horizontal ribs, k, which 85 enter grooves k' formed in the outer sides of the lug J, whereby the washer is firmly supported on the lug against vertical displacement, thereby holding the bolt I securely in place. The cone h'' is provided on its upper 90 side with similar ribs, k'', which enter grooves in the inner side of the adjacent lug J, whereby this end of the supporting-bolt I is similarly secured. The interlocking ribs and grooves of the cone h'' and lug J hold the cone 95 from turning. Upon loosening the nut i' the washer can be raised or lowered on the lug J, thereby adjusting the height of the bolt I and turning the front end of the backbone forwardly or backwardly, whereby the rake of 100 the machine is reduced or increased. This enables the rider to adjust the machine to the best application of his strength on good roads or for safety on poor roads, or a beginner can adjust it for safety while learning to ride and 105 afterward reduce the rake and adjust the machine for a more direct application of power. The bearings of the rear wheel are adjusted in the usual manner by loosening the nut i' and screwing up the cone h''.

In the construction represented in Figs. 11 and 13 the slot j is extended downwardly through the lower end of the lug J, dividing the latter into two vertical jaws. The outer sides of the jaws are provided with two vertical 115 rows of openings, m, in which engage pins n, secured to the washer K, whereby the washer is supported on the lug and the jaws are prevented from spreading.

In the construction represented in Fig. 12 120 the lug J is provided with a series of holes for the reception of the supporting-bolt I. This construction is less expensive and very strong, but not as convenient, because it necessitates the removal of the supporting-bolt 125 from the wheel in order to adjust the rake of the machine.

I claim as my invention—

1. The combination, with the steering-head and spindle, of an adjusting-screw embracing 130 the upper end of the spindle, and a tubular check-nut arranged between the adjusting-

screw and steering-head, substantially as set forth.

2. The combination, with the steering-head and spindle, of an adjusting-screw embracing 5 the upper end of the spindle, and a tubular check-nut provided with a tapering portion and arranged between the adjusting-screw and steering-head, whereby the nut is wedged between said parts in tightening it, substantially as set forth.

3. The combination, with the steering-head and spindle, of an adjusting-screw embracing the upper end of the spindle, and a tapering tubular check-nut split lengthwise, and arranged 15 between the adjusting-screw and steering-head, substantially as set forth.

4. The combination, with the steering-head and neck A', of the dust-cap E, and a spring-clamp, F, seated in the neck and interposed 20 between the neck and the dust-cap to press the latter against the steering-head, substantially as set forth.

5. The combination, with the steering-head and neck A', of the dust-cap E, and the spring-clamp F, seated against a shoulder in the neck 25 A', and provided with projections f', which enter openings in the dust-cap, substantially as set forth.

6. The combination, with the perch and the rear fork rigidly secured thereto, of the rear 30 wheel, a support for the latter made vertically adjustable in the rear fork, and means, substantially as described, whereby the wheel-support is rigidly secured in the fork after adjustment, substantially as set forth. 35

7. The combination, with the rear fork having lugs J, provided with vertical slots j, of the rear wheel, H, the supporting-bolt I, provided with nut i', washer K, and interlocking 40 depressions and projections formed on the contiguous faces of the washer and lug, substantially as set forth.

8. The combination, with the rear fork having lug J, provided with vertical slots j, of the rear wheel, H, the supporting-bolt I, provided with nut i', cone h', and the washer K, and cone h², having projections interlocking 45 with depressions in the contiguous sides of the lugs J, substantially as set forth.

Witness my hand this 28th day of February, 50
1885.
